UNITED STATES PATENT OFFICE.

CARL C. KING, OF EVANSVILLE, INDIANA.

COMBINED COLLAR-BUTTON AND NECKTIE-RETAINER.

SPECIFICATION forming part of Letters Patent No. 680,047, dated August 6, 1901.

Application filed December 11, 1900. Serial No. 39,501. (No model.)

To all whom it may concern:

Be it known that I, CARL C. KING, a citizen of the United States, residing at Evansville, in the county of Vanderburgh and State of Indiana, have invented a new and useful Combined Collar-Button and Necktie-Retainer, of which the following is a specification.

This invention relates to improvements in necktie-fasteners; and the object is to provide an effective, simple, and ornamental device for retaining the necktie in position which may be conveniently attached to the collar-button and removed therefrom.

With the above object in view the invention consists in the novel features of construction hereinafter fully described, particularly pointed out in the claims, and clearly illustrated by the accompanying drawings, in which—

20 Figure 1 is a perspective view of a construction embodying my invention, the same being shown in operative position; Fig. 2, a detail section through one of the jaws; Fig. 3, a detail of one of the jaws separated; Fig. 4, 25 a detail perspective view of the plate and button detached, the jaws being removed; Fig. 5, a detail face view, partly in section, of my improved necktie-holder and collar-button complete. Fig. 6 is a transverse section of 30 the same on the line 6 6 of Fig. 5. Fig. 7 is a detail of a modified construction, and Fig. 8 illustrates another modification.

Referring now more particularly to the accompanying drawings, A designates a plate 35 having a casing B arranged at its center and upon its outer face and provided with a central perforation C to receive the notched end of the shaft D of the collar-button E. Arranged in this casing and having pressure 40 portion F projecting normally through an opening in the casing is a depressible locking member G, formed with an opening H, registering with the perforations C of the casing when the locking member is depressed, but 45 having its lower wall normally covering a portion of said opening. This locking member is held normally in an upward position by means of a spring I, positioned in the casing. When the notched end of the shank of the 50 collar-button enters the opening of the cas-

ing, said locking member is depressed until the notch is in position to be engaged, which engagement is effected by the upward movement of said member, caused by the section of the spring. The plate is thus held in position upon the collar-button until the locking member is depressed to disengage the notch of the shank of the button.

55 Secured to the plate at each end is a vertically-extending plate J, having outwardly extending flanges K formed intermediately of its ends, which flanges are formed with notches or teeth K', as clearly illustrated. At its upper end said plate is formed with a spring-arm L and upon each side of said arm 60 with a loop M. This plate, constructed as above set forth, constitutes the fixed jaw of the necktie fastener or clamp.

Hinged to the stationary jaws are the stationary jaws N, carrying pintles, which are 70 positioned in the loops M and formed with spring-arms O, bent to engage arms L of the stationary jaws, so as to retain said swinging member either in a closed or opened position. Said member is formed on its inner side with 75 points or projections P to coact with the teeth or notches of the stationary jaw, so as to securely hold the tie. Each of said movable jaws upon its outer side is ornamented, as 80 illustrated, so as to present a neat and attractive appearance.

In operation the plate is attached to the collar-button and the band of the tie or that portion extending around the collar inserted between the jaws, where it is firmly held. The 85 fastener will then present the appearance of two ornamental plates disposed on opposite sides of the tie proper, and these plates may be made as attractive as may be desired by engraving the same with any desired pattern 90 and even mounting a stone thereon.

In the construction shown in Fig. 7 the locking member Q' is in the shape of a split ring of spring metal positioned in the casing B and having a finger portion projecting through 95 the opening in the upper wall thereof. One end of the split ring is bent inwardly to form an engaging arm R', which normally covers a portion of the opening C of the plate, so as to engage the notched end of the collar-button 100.

shank. The other end of the split ring constitutes a spring-arm and normally holds the engaging arm R' in its upward position.

In the modified construction illustrated in Fig. 8 I have dispensed with the casing and spring locking member and formed the body portion of the fastener of a piece of wire bent in the form of an elongated loop, the upper portion Q of which is formed at its center with a downwardly-extending spring-loop R to embrace the collar-button.

It will be understood that various modifications might be made in the construction for attaching the fastener to the collar-button, and I do not desire to limit myself to the exact details herein shown and described for accomplishing this purpose.

Having thus fully described my invention, what I claim as new, and desire to secure by Letters Patent, is—

1. A necktie-fastener, comprising a plate carrying means intermediately of its ends for attaching it to a collar-button, stationary jaws at the respective ends of said plate and disposed transversely thereof, and swinging jaws pivoted at one end to the stationary jaws, substantially as described.

2. A necktie-fastener, comprising a body portion having means intermediately of its ends for attaching it to a collar-button, stationary jaws at the ends of said body portion having teeth formed thereon, swinging jaws pivoted to the stationary jaws, and also car-

rying engaging portions or teeth, and means for retaining said swinging jaws in a closed position, substantially as described.

3. The combination with a collar-button, having a notched shank, of a plate formed intermediately of its ends with a casing having an opening for the insertion of said shank, a 40 depressible locking member positioned in said casing for engaging the notch of the shank and preventing disengagement thereof from the plate, a spring for holding said depressible member normally outward, fixed jaws carried by the ends of said plate, and swinging jaws pivoted to said fixed jaws, substantially as set forth.

4. A necktie-fastener, comprising a body portion having means intermediately of its 50 ends for attaching the same to a collar-button, stationary jaws carried by the respective ends of said plates, each of said jaws formed at one end with a centrally-disposed spring-arm and loops disposed on opposite sides of 55 said arm and at some distance inward from the free end of the arm, and swinging jaws having pintles engaging in said loops of the stationary jaws, and formed with centrally-disposed spring-arms for coacting with the 60 spring-arms of the stationary jaws, substantially as set forth.

CARL C. KING.
